ELECTRIC FURNACE.

No. 923,018.

Specification of Letters Patent.

Patented May 25, 1909.

Application filed March 19, 1907. Serial No. 363,292.

To all whom it may concern:

Be it known that we, FRÉDÉRIC MARIE CHAPLET and ALEXANDRE RÉMOND, citizens of the Republic of France, and residents the 5 first of Laval, the second of Paris, have invented a new and useful Electric Furnace; which electric furnace is fully set forth in the following specification.

This invention relates to electric furnaces, 10 and the object of our improvements is to simplify the construction of such furnaces.

Referring to the accompanying drawings, which represent embodiments of the present invention, Figure 1 is a longitudinal section 15 of a furnace; Fig. 2 is a top view thereof, the dome F being removed; Figs. 3 and 4 are views (like 1 and 2) of a modification, and Fig. 5 is a cross-section of either form of furnace, in order to show the form of 20 passageway hereinafter mentioned.

The furnace comprises two distinct tanks or compartments A and B, which may be of any desired form. Compartment A will, as shown, usually be of greater capacity than 25 tank B.

Electrodes, for producing the arc or electrical resistance, in order to effect the fusion of the contents of the tanks or compartments, dip downwardly into said tanks or 30 compartments. In Fig. 1, electrode C (preferably of graphite) dips into compartment A, while electrode C¹ (of metal or carbon, according to circumstances) dips into compartment B. Both electrodes are properly 35 connected with conductors, and constitute parts of the fusing circuit. In either tank, more than one electrode may be used. Fig. 40 3 shows compartment A provided with two electrodes C and C¹, which is preferred in the case of large compartments. Tank A may, as shown, be provided with a suitable cover or dome F, and the electrode or electrodes—movable either mechanically or by hand—slidably fit through openings thereof.

45 It is the characteristic and essential feature of this invention that the sole means of communication between the tanks or compartments A and B is by means of a passageway D formed in the furnace itself and continuing from one tank to the other and in the bottom of both.

During use of the furnace, the passageway is filled with conducting material, which may be of the same nature as the product to 50 be treated—such as iron or steel, for example. This passageway insures electrical

communication between compartments A and B. Whatever its form, for the desired results, it need comply only with the following conditions:—it should form a sufficiently 60 tight joint for retaining the conducting material even if fused, it should be sufficiently long to permit of ready cooling either of tank B or electrode C¹, of sufficient cross-section to prevent excessive resistance to the 65 passage of current; its construction should be such that at the time of running off the product from tank A, the liquid in the passageway is not discharged sufficiently to interrupt the electric current. 70

Tapping hole E or E¹ (or both) is formed in the furnace, at an appropriate level, preferably above the passageway D, for running off the substance treated in the tank A.

The furnace is composed of any suitable 75 refractory substance, non-conductive of electricity, and the same is true of cover F (when used) which may be silicia, magnesia, etc., or even of carbon if a resistance to exceedingly high temperature is required. 80

If desired, the tank B or its contents may be cold or cooled artificially or naturally.

With a furnace of the kind illustrated and described, it is possible, to re-fuse the metals or metallic alloys; to reduce the oxids in 85 order to directly obtain metals either pure or alloyed; or to refine metals.

The furnace is particularly adapted to the manufacture of exceedingly pure steels from ordinary primary materials which are 90 relatively impure.

What we claim is:

In an electric furnace having two distinct compartments and a communicating passage forming the connecting means between the 95 said compartments and containing the conducting material, an open compartment receiving a carbon or metal electrode plunging into the conducting mass; a closed compartment or laboratory receiving a carbon electrode forming an arc with the molten metallic surface, and a tap formed in the wall of the furnace above the passage connecting the two compartments. 100

In testimony whereof we have signed this 105 specification in the presence of two subscribing witnesses.

FRÉDÉRIC MARIE CHAPLET.

ALEXANDRE RÉMOND.
